ABSTRACT OF THE DISCLOSURE

Protection devices for fly-shuttle loom operable individually from opposing shuttle boxes for initiating loom-stoppage prior to beat-up if the shuttle is not present or is not properly positioned within its intended box.

BACKGROUND OF THE INVENTION

This invention pertains to weaving looms of the fly-shuttle type and, more particularly, to an improved mechanical control mechanism for the automatic cessation of such looms.

It is a general object of the invention to provide an improved automatic means for stopping a loom in the event of improper shuttle boxing.

A further object is that of providing an improved means for stopping a loom which requires considerably less inertia to perform its intended function than the conventional means well known in the weaving art.

Another object of the invention is that of providing a loom stopping mechanism which will perform its intended function with fewer cooperating elements, thereby reducing the weight of the mechanism which in known devices is a contributing factor in the breakage of various loom components.

A still further object is that of providing such a mechanism whereby the components in each shuttle box which initiate stoppage of a loom are adapted to function independently of similar components in the opposed shuttle box.

Another object is that of devising such a mechanism which by performing its function more efficiently with fewer cooperating components, provides a relatively inexpensive and economically desirable loom stopping mechanism.

Further objects and advantages of the invention will become apparent from the following more detailed disclosure.

The greater number of present day looms now being furnished to the weaving industry utilize a unitary type clutch-brake motor as their source of power and the loom stopping mechanism according to the instant invention is adapted to cooperate with motors of this type during the performance of its intended function.

It is common practice in the above-mentioned looms to provide a means for stopping a loom automatically in the event of improper shuttle boxing, such as a shuttle not entering a shuttle box at the precise moment it is timed to be received therein. This manner of abruptly stopping a loom is commonly referred to as a "bang-off," and is necessary to prevent extensive damage to the shuttle as well as the many warp yarns that extend transversely of the lay.

The conventional and well-known means utilized to effect a loom bang-off includes a lay supported protector rod which is oscillatable in a known manner and includes frog engageable dagger fingers adjacent each end thereof. With this arrangement, linkage between the shuttle box and the protector rod will lift the dagger fingers a sufficient distance to clear the frogs when the shuttle is

2

properly received and positioned within the shuttle box. In the event a shuttle is late, or in other words, improperly received or positioned within a shuttle box, the aforementioned linkage will fail to lift the dagger fingers and the latter will be caused to engage the frogs creating a so-called bang-off which brings the loom to an abrupt stop.

This manner of loom stopping has presented conditions which are considered undesirable in modern day looms, for as is well known to those conversant with the art, modern looms have a substantially heavier lay construction and are adapted to operate at greater speeds than the older models of looms.

This heavier lay construction and the higher speeds at which present looms are caused to operate are at time of bang-off contributing factors in the cause of breakage of various loom components such as loom frames and those cooperating elements utilized to effect the actual stopping of the loom.

The improved loom stopping mechanism according to the instant invention provides an improved means for automatically stopping a loom and has eliminated the well-known conventional bang-off components which include the protector rod, dagger fingers and frogs.

The mechanism of the invention is adapted to function independently of the shipper motion elements which provide the means for manually starting and stopping a loom.

The invention includes pivotable shuttle sensing elements which form a part of each shuttle box and the sensing element of one box is adapted to function independently of the similar element in the opposite box.

These sensing elements are in the form of pivotable members which extend upwardly into the shuttle box and into the pathway of the shuttle when it is received therein. When in the shuttle pathway position, these elements are maintained in that position by means of the lower ends making contact with magnet members suitably positioned beneath the lower surface of each shuttle box. As a shuttle enters a box its lower surface contacts the sensing member and pivots it to a non-interfering position.

The sensing element is held in the non-interfering position by making contact with another magnet member which is suitably assembled flush with the lower surface of the shuttle box. A re-set rod disposed immediately beneath the lay and extending longitudinally therewith is effective in moving each sensing member from a non-interfering position back to the shuttle pathway position just prior to the shuttle entering either of the two shuttle boxes. As a shuttle is caused to leave a shuttle box, the picker stick

at the end of its power stroke contacts one end of the re-set rod and moves it a sufficient distance to cause a re-set finger, which is fixedly attached to the re-set rod, to strike the lower portion of the sensing element in the opposite shuttle box moving the same to the shuttle pathway position in readiness for the incoming shuttle.

If a sensing element fails to be actuated, or in other words, fails to be pivoted to the non-interfering position, an indicator latch, which is mechanically linked to said element and pivotable therewith, contacts a vertically disposed pivotable lever on the forward movement of the lay and pivots the upper portion of said lever in a like direction.

This pivotable lever is, through the combination of linkage elements, interconnected with the operating lever of the clutch-brake motor heretofore mentioned and is effective in applying the brake of said motor thereby stopping the loom. A co-pending patent application No. 476,979 filed Aug. 3, 1965, shows and describes a motor disconnect latch with which the linkages and sensing elements according to the instant invention are adapted to

cooperate to effect the cessation of a loom.

The invention will hereinafter be described in greater

detail by reference to a specific embodiment thereof as illustrated in the accompanying figures of drawing, wherein:

FIG. 1 is a view in front elevation of a portion of the right-hand side of a loom showing one of the shuttle sensing elements according to the invention as applied thereto and the means by which said element is reset to the shuttle pathway position;

FIG. 2 is a plan view of a portion of the mechanism shown in FIG. 1 showing the shuttle sensing element and the cooperating components pivotable therewith for initiating stoppage of a loom;

FIG. 3 is a view in end elevation and partially in section of the mechanism shown in FIG. 2;

FIG. 4 is a perspective view of a portion of a loom lay beam as seen looking at the underside thereof and showing the means for supporting and adjusting the sensing element re-set rod;

FIG. 5 is a perspective view of the control linkage at the right-hand side of a loom for actuating the loom motor's disconnect latch and also the lever arrangement which permits loom stoppage indications from the left-hand shuttle box to be transmitted independently of right-hand control linkages; and

FIG. 6 is a perspective view of the control linkage at the left-hand side of the loom.

Referring now to the figures of drawing, a portion of a loom's right-hand shuttle box is depicted in FIG. 1 showing the shuttle sensing element in position along with only the essential cooperating components displayed.

As the general construction and operation of this type of loom are well known and familiar to those conversant with the weaving art, and as the invention is entirely concerned with a novel protection mechanism for stopping a loom, it is only considered necessary here to illustrate and describe those parts of a loom directly concerned with a preferred form of the present invention.

A loom includes among other conventional parts a pair of sword members 10 (a portion of one only shown in FIGS. 1, 2, and 3) which are disposed in spaced relation and caused to swing to and fro during the performance of their intended function. A lay beam 11 which traverses the width of the loom is supported by the sword members immediately below the forward upper surfaces of the latter. Lay ends 12 (one only shown in FIGS. 1, 2, and 3) are fixedly attached to the upper end portions of the lay and form a part of the shuttle boxes disposed at each end of the lay beam 11.

Other conventional components of the shuttle boxes not shown include such items as the box plates and binders.

Picker sticks 13 having pickers 14 attached to the upper ends thereof (one only shown in FIG. 1) function in a conventional manner to cause a shuttle 15 to be picked back and forth across the lay beam.

The shuttle sensing element according to the invention is depicted generally in FIGS. 1, 2, and 3 by numeral 16. This element is fabricated from flat, metallic stock and being generally arcuated it is so disposed as to extend upwardly from an assembly point beneath the lay beam, through an appropriate slot in the latter, and into the confines of the shuttle box.

The sensing element 16 is fixedly supported for pivoting movement adjacent the forward end of a generally horizontally disposed rod member 17 by means of screws 18 and 19 (FIG. 2) which are adapted to pass through spaced apertures in said element, through aligned holes in the rod member, and then assemble in aligned tapped holes provided in an anchor plate 20.

As seen looking from the front of a loom, rod member 17 extends in a rearward direction and passes through a hole 21 provided in the sword 10 (FIG. 3). Rod member 17 is journaled for oscillating movement in hole 21 by means of bushings 22 and 23 which assemble in a counter bore provided at each end of said hole.

The sensing element 16 is pivotable in a manner to be more fully described hereinafter between the limits of the solid and phantom line positions shown in FIG. 1. This element is maintained in one or the other of the above positions by means of magnet members disposed so as to make contact with said member on surfaces adjacent its ends.

When the sensing element is in the non-interfering or solid line position shown in FIG. 1, it is maintained in this position by a magnet member 24 which assembles in the shuttle box flush with the lower surface thereof.

When the sensing element is in the phantom line or shuttle pathway position, that surface adjacent the lowermost end of said element is in contact with a magnet member 25. This magnet member is suitably attached to a housing bracket 26 (FIG. 1) which assembles to a support bracket 27 by means of cap screws 28 and 29. Support bracket 27 depends from an inner rib surface 30 (FIGS. 1 and 3) of the lay and attaches to the latter by means of cap screws 31 and 32.

A re-set rod 33 is supported immediately beneath the lay beam 11 and extends longitudinally therewith. This re-set rod is of a length which permits the ends thereof to be contacted by the picker sticks at the end of their power strokes and to cause said rod to move a short distance in a lineal direction. The ends of the rod 33 are provided with contact plugs (one only shown in FIG. 1) which serve as a bumper element for the picker sticks. This rod extends through an aperture 35 provided in the lower central portion of the sensing element (FIG. 3) and also passes through and is supported by so-called silent block bushings 36 (one only shown in FIG. 1). These bushings include an inner sleeve through which the rod 33 passes, and an outer shell with a resilient rubber-like material therebetween which is bonded to both said sleeve and outer shell. The bushings are housed in a support bracket 37 which is attached to the sword 10 by means of a cap screw 38.

A pair of collar members 39 and 40 (FIG. 1) are fixedly assembled on the rod 33 and are positioned on each side of the support bracket 37 in abutting relation with the inner sleeve of the bushing 36. The collar members 39 and 40 being fixedly positioned on rod 33 and in abutting relation with the inner sleeve of the bushing 36 tend to maintain said rod in a relatively fixed position; however, when the picker stick strikes the end of the rod at the end of its power stroke, one of the bushings in contact with the inner sleeve of the bushing 36 will be forced against said sleeve. This movement will cause a deflection of the resilient rubber-like material and rod 33 will be moved a short distance in a lineal direction. When the forces of the picker stick's power stroke have dissipated, rod 33 will immediately return to its initial position by the return of the rubber-like material to the shape in which it was formed. The means by which the sensing elements is reset from the non-interfering position to the shuttle pathway position will now be described.

The sensing element 16 at the point of assembly with the rod member 17 is provided with a generally L-shaped reset finger 41 which is pivotable with said element and assembles between the latter and the anchor plate 20. This reset finger extends in a generally downward direction with the foot portion thereof extending in a plane substantially horizontal and toward the center of the loom. In close proximity with the end of the foot portion of the reset finger there is provided a reset collar 42 having a depending lug portion 43. Collar 42 is fixedly positioned on rod 33 and the lug portion 43 is adapted to strike the foot portion of the reset finger 41 when said rod is caused to move in a lineal direction whereby the sensing element is pivoted to the shuttle pathway position.

FIGS. 1, 2, and 3 only show the sensing element as applied to the right-hand side of a loom; however, it should be understood that a similar element functions on the left side in a like manner and cooperates with similar

components. The reset rod 33 cooperates with both sensing elements and FIG. 4 illustrates a center guide support for said rod which is depicted generally by numeral 44. This guide support assembles to the underside of the lay in a generally centralized position relative to the length thereof by means of cap screws 45 (one only shown in FIG. 4).

The manner in which the pivotable sensing elements are effective in initiating the stopping of a loom will now be described.

The horizontally disposed rod member 17 is provided on that end opposite the end to which the sensing element 16 assembles, with a sensing latch 46. As shown in FIG. 1, this latch is pivotable with the sensing element between the limits of the phantom and solid line positions shown.

A vertically disposed lever 47 (upper portion only shown in FIGS. 3 and 5) is pivotably attached at its lower end by any suitable means to the loom frame. A linkage rod 48 is pivotably attached to lever 47 at a point adjacent its upper end and extending rearwardly therefrom the opposite end of said rod extends through an opening in the lower portion of the top girt end 49 and is pivotably attached to one arm of a bell crank lever 50. The second arm of this bell crank lever 50 is bifurcated as at 51 and is disposed so as to permit the loom motor disconnect rod 52 to pass between the bifurcated portion thereof. A driving collar 53 is assembled in a fixed manner on rod 52 by means of a set screw 54 and is in abutting relation with the bifurcated portion of bell crank 50. Bell crank lever 50 is adapted to be moved in a clockwise direction as seen looking from the top thereof and such movement which will be more fully described hereinafter, will cause the bifurcated portion of said lever to push against collar 53 and move rod 52 in the direction of the indicating arrow 54' shown in FIG. 5. Rod 52 extends to the motor disconnect latch shown and described in the aforementioned patent application, and such movement effects immediate cessation of the loom.

The linkage means by which the sensing element in the left-hand shuttle box is able to transmit its indications for loom stoppage independently of the right-hand shuttle box will now be described.

The motor disconnect rod 52 extends through and beyond the limits of the bifurcated portion of the bell crank lever 50 and the end of said rod as shown in FIG. 5 is in abutting relation with the hooked end portion 55 of a double armed lever generally indicated by numeral 56. Lever 56 is mounted for pivotable movement on a mounting bracket 57 by means of a bolt 58 passing through an aperture (not shown) intermediate the ends of said lever. Bracket 57 assembles as shown in FIG. 5 to the top girt end 49 by means of bolts 59 and 60. That end of the double armed lever 56 opposite the hooked end 55 is identified by numeral 61 and has a driving rod 62 pivotably attached thereto by means of a bolt 63 and nut 64. Driving rod 62 extends toward the left-hand side of the loom and as shown in FIG. 6 the opposite end thereof is pivotably attached to one arm of a bell crank lever 65. This bell crank lever is supported by a bracket member 66 which is attached to the left-hand top girt end 67 by means of bolts 68 and 69.

A linkage rod 70 is pivotably assembled at one end to the second arm 71 of the bell crank lever 65 and extending in a generally forward direction, the opposite end of said rod is assembled in a like manner to a vertically disposed lever 72 as at 73. This lever functions in the same manner as lever 47 disposed at the right-hand side of the loom and when caused to be tilted forwardly it moves linkage rod 70 in the direction of the indicating arrow 74 shown in FIG. 6. Such movement will cause the bell crank lever 65 to move the driving rod 62 in the direction of the indicating arrows 75 (FIGS. 5 and 6) thereby moving the double armed lever 56 in a clockwise direction. It can now be easily seen that movement of

5 the motor disconnect rod 52 (FIG. 5) can be actuated independently by either the double armed lever 56 which is controlled by the linkage arrangement from the left-hand side of the loom or the bell crank lever 50 that is controlled by the linkage on the right-hand side of the loom.

In operation, a shuttle is picked back and forth across the loom lay beam in a conventional and well-known manner. As the shuttle enters either the right- or left-hand shuttle box, it contacts the shuttle sensing element 16 and pivots it to a non-interfering position or a position whereby the upper portion thereof becomes flush with the lower surface of the shuttle box where it is maintained in this position by the magnet member 24. As the shuttle is picked from a shuttle box, the picker stick at the end of its power stroke strikes the end of the re-set rod moving the same a short distance in a lineal direction. This movement is sufficient to cause the reset collar 42 on the re-set rod at the opposite side of the loom to strike the reset finger 41 of the sensing element at this side of loom causing this sensing element to be pivoted to the shuttle pathway position and in readiness for the incoming shuttle. The sensing element is held in this position until shuttle arrival by the magnet member 25 disposed adjacent the lower portion of said element. The procedure is reversed when the shuttle is picked from this box moving the re-set rod in the opposite direction to re-set the other of the two sensing elements.

As heretofore described, the sensing latches 46 at each side of the loom are pivotable with their particular sensing element 16. As a shuttle is received into a shuttle box, the lay is moving toward front center and the pivoting of the sensing element by the shuttle to the non-interfering position pivots its sensing latch 46 to the phantom line position shown in FIG. 1 which is a sufficient distance to clear the upper end portion of the vertically disposed lever 47 or 72 depending, of course, in which shuttle box the shuttle is being received. In the event a shuttle should fail to enter either shuttle box at the precise time it is due, the sensing latch will contact the upper end portion of one or the other of the levers 47 or 72 causing it to be tilted forwardly. This motion will actuate the linkage extending rearwardly from the particular lever affected and will cause the disconnect rod 52 to be moved a sufficient distance to effect loom stoppage.

While one embodiment of the invention has been disclosed, it is to be understood that the inventive concept may be carried out in a number of ways. This invention is, therefore, not to be limited to the precise details described, but is intended to embrace all variations and modifications thereof falling within the spirit of the invention and the scope of the claims.

We claim:

1. In a fly shuttle loom having a lay, aligned and oppositely disposed shuttle boxes forming the ends of said lay for receiving a shuttle as it is caused to travel thereacross, the improvement which comprises shuttle sensing elements mounted within each of said shuttle boxes, said sensing elements being pivotably mounted for movement from a shuttle pathway position to a non-interfering position when contacted by said shuttle, means for maintaining said sensing elements in each of said positions and a further means for returning each of said sensing elements individually to the shuttle pathway position prior to said shuttle being received into each of said shuttle boxes.

2. The mechanism according to claim 1 wherein said fly shuttle loom includes a picker stick cooperating with each of said shuttle boxes for propelling said shuttle across said lay, said further means comprising a re-set rod adapted to be moved in a lineal direction by said picker stick to pivot the sensing element in the opposite shuttle box to said shuttle pathway position.

3. The mechanism according to claim 1 wherein said

means for maintaining said sensing element in each of said positions includes magnet members disposed so as to contact said elements adjacent their ends in each of said positions.

4. The mechanism according to claim 1 wherein said loom includes first linkage means for stopping said loom and further linkage means movable with said sensing elements and adapted to cooperate with said first linkage means for stopping said loom should said shuttle fail to be sensed at the precise time it is due to arrive in each of said shuttle boxes.

5. The mechanism according to claim 4 wherein said further linkage means includes linkage elements for

transmitting independent indications from each of said sensing elements to said first linkage means to effect cessation of said loom.
